UNITED STATES PATENT OFFICE.

HAGE WEBSTER HUCKNALL, OF ELYRIA, OHIO, ASSIGNOR TO AMERICAN LACE MFG. CO., OF ELYRIA, OHIO, A CORPORATION OF OHIO.

CAMISOLE LACE FABRIC.

1,280,035.

Specification of Letters Patent. Patented Sept. 24, 1918.

Application filed December 5, 1917. Serial No. 205,544.

To all whom it may concern:

Be it known that I, HAGE WEBSTER HUCKNALL, a citizen of the United States, and a resident of Elyria, in the county of Lorain 5 and State of Ohio, have invented a new and Improved Camisole Lace Fabric, of which the following is a full, clear, and exact description.

This invention relates to a camisole and 10 lace fabric for making the same.

Heretofore camisoles have been made of a plurality of pieces which are sewed together. For instance, the body piece has sewed to the top and bottom edges strips of 15 beading and a strip of edging on the lower beading, and to the upper beading is sewed the shoulder strap pieces of the camisole. Because of this method of manufacture camisoles are high-priced and the demand 20 is accordingly limited.

The object of the present invention is to provide a camisole fabric which is made of one piece of lace which is sold in strip form with cut-out portions along the top of the 25 strip, whereby the remaining portions constitute shoulder straps, the corresponding ones of which are tied together by a bow, the strip including therefore the body, the beading, the bottom edging and the shoulder straps. In weaving the lace the web is 30 of such width that it includes a plurality of camisole strips which are cut and separated and made up into bolts from which the camisole material is sold by the yard. 35 As a result of this method of manufacture camisoles of very neat and attractive design can be made at very low cost compared with the former method of making camisoles.

For a more complete understanding of the 40 invention reference is to be had to the following description and claims taken in connection with the accompanying drawings, which illustrate one embodiment of the invention and wherein similar characters of 45 reference indicate corresponding parts in all the views, in which—

Figure 1 is a plan view of a web of lace as it comes from the lace weaving machine, the web being composed of a plurality of 50 strips which are cut along the dotted lines for the camisole blanks;

Fig. 2 is a plan view of a complete camisole blank; and

Figs. 3 and 4 are views of the complete 55 camisole shown applied to a figure.

Referring to Fig. 1 of the drawings, A designates a portion of a web of lace as it comes from the lace weaving machine, the web being composed of a plurality of strips 1, 2 and 3, which are cut or separated on 60 the longitudinal lines 4, so that the strips will be just wide enough for the making of a camisole. Each strip comprises a body 5, upper and lower beadings 6 and 7 and edging 8, and a shoulder strap section 9. The 65 lace may be made according to any desired design, but the portion 9 is preferably composed of diamond or equivalent repeats 10 which lend themselves more favorably for the cutting out of the shoulder strap members of the camisole. In Fig. 1 the longitudinal zigzag lines indicate the manner in which the portions 9 of the camisole strips are cut out to leave the shoulder strap members 11. The vertical dotted lines 12 indicate 70 where the strips are cut transversely to produce the blanks of full length each for a camisole. It will be noted that the two central shoulder strap members are arranged close together and these constitute back 75 members, and the outer members are separated by wide recesses 13, as clearly indicated in Fig. 2, from the inner members, and these outer members constitute the front portions of the shoulder straps. These 80 recesses 13 provide the armholes of the camisole when the points or apices 14 of the corresponding front and rear shoulder strap members are fastened together, as for instance, by a bow of ribbon 15, Figs. 3 and 90 4. Draw strings 16 and 17 are passed through the upper and lower beadings 6 and 7 and they serve to draw the camisole close around the body of the wearer in the 95 usual manner.

It will be obvious that from a camisole strip as herein proposed the material can be bought at an ordinary dry goods store in the desired length, and the making of the camisole is a simple matter, since it only remains to tie the tips of the strap members properly together and insert the draw strings.

From the foregoing description taken in connection with the accompanying drawings 105 the advantages of the construction and method of operation will be readily understood by those skilled in the art to which the invention appertains, and while I have described the principle of operation, together 110

with the article which I now consider to be the best embodiment thereof, I desire to have it understood that the article shown is merely illustrative and that such changes 5 may be made when desired as fall within the scope of the appended claims.

Having thus described my invention, I claim as new and desire to secure by Letters Patent:

- 10 1. A one-piece lace camisole comprising a body-encircling portion and triangular shoulder straps, said shoulder straps being made of diamond repeats so arranged that the outer edges of certain of the repeats 15 form the edges of the shoulder straps.
2. A lace camisole comprising a body portion having integral shoulder straps, said shoulder straps being entirely made up of

repeats, and the edges of certain of the repeats forming the edges of the shoulder 20 straps.

3. A seamless camisole comprising a body portion having shoulder straps, said body portion and shoulder straps being a single-piece lace fabric and each strap having a 25 plurality of designs, the designs along the edges of the shoulder straps having their outer edges coinciding with the shoulder strap edges.

4. A lace camisole comprising a seamless 30 body having upper and lower beadings, and shoulder straps having seamless connection with the upper beading, and tie ribbons for connecting the tips of corresponding shoulder straps.

HAGE WEBSTER HUCKNALL.
